UNITED STATES PATENT OFFICE

90,515

DESIGN FOR A RACK

Lee O. Taylor, Muskegon, Mich., assignor to Muskegon Bennett Corporation, Muskegon,
Mich., a Corporation of Michigan

Application May 15, 1933. Serial No. 48,120

Term of patent 3½ years

To all whom it may concern:

Be it known that I, LEE O. TAYLOR, a citizen of the United States, residing at the city of Muskegon, in the county of Muskegon and State of Michigan, have invented a new, original, and ornamental Design for a Rack, of which the following is a specification, reference being had to the accompanying drawing, forming a part thereof.

The figure is a perspective view of a rack, showing my new design.

I claim:

The ornamental design for a rack, as shown.

LEE O. TAYLOR.
